United States Patent Office

Des. 192,407
Patented Mar. 20, 1962

192,407

SIGN

John G. Purdy, 708 Mary St., Dowagiac, Mich.

Filed Mar. 29, 1961, Ser. No. 64,536

Term of patent 14 years

(Cl. D1—12)

FIG. 2

FIG. 1

FIG. 1 is a side elevational view of a sign embodying my new design, the opposite side being substantially the same as the side shown; and

FIG. 2 is an end elevational view taken from the left of FIG. 1.

I claim:

The ornamental design for a sign, as shown and described.
